Primary Examiner — Cary M Robinson*Assistant Examiner* — Emily Anna Saunders(74) *Attorney, Agent, or Firm* — Daniel M. Cohn; Howard M. Cohn(57) **CLAIM**

The ornamental design for an adjustable puzzle platform, as shown and described.

DESCRIPTION

FIG. 1 is a front, left side perspective view of an adjustable puzzle platform, showing my new design;

FIG. 2 is a rear, right side perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof; and,

FIG. 9 is a front, left side perspective view of the adjustable puzzle platform in an alternate configuration.

The broken lines in the drawings depict portions of the adjustable puzzle platform that form no part of the claimed design.

1 Claim, 9 Drawing Sheets(56)
